UNITED STATES PATENT OFFICE.

JOHN D. WALL, OF MINNEAPOLIS, MINNESOTA.

FRAME ATTACHMENT FOR CARPENTERS' SQUARES.

1,282,999.

Specification of Letters Patent. Patented Oct. 23, 1918.

Application filed November 17, 1917. Serial No. 202,487.

To all whom it may concern:

Be it known that I, JOHN D. WALL, a citizen of the United States, residing at Minneapolis, in the county of Hennepin and State of Minnesota, have invented certain new and useful Improvements in Frame Attachments for Carpenters' Squares; and I do hereby declare the following to be a full, clear, and exact description of the invention, such as will enable others skilled in the art to which it appertains to make and use the same.

My invention relates to improvements in framing attachments for use in connection with an ordinary steel square, commonly used by carpenters and other mechanics, and is in the nature of an improvement on my U. S. Letters Patent, 1,060,588, issued April 29, 1913.

While all carpenters necessarily use the square in their work, a comparatively few have a sufficient knowledge of its use to enable them to accurately lay out and cut the necessary timbers required in the construction of the roof of a house or other building. Furthermore, a great many carpenters have not had in their schooling sufficient mathematics to enable them to thoroughly understand technical problems that can be solved by the use of the ordinary square. To bring the so-called technical square, as might be said, down to the everyday mechanic, whereby he can very quickly and accurately obtain all difficult and technical cuts in roof work, hopper work, and the like, I provide an attachment for the ordinary square, by the use of which all these technical problems are mechanically solved.

To the above end, the invention consists of the novel devices and combinations of devices hereinafter described and defined in the claims.

In the accompanying drawings, which illustrate the invention, like characters indicate like parts throughout the several views.

Referring to the drawings:

Figure 1 is a plan view of a square having the improved framing attachment applied thereto, said square and attachment being positioned on a timber.

Fig. 2 is a front elevation of a square and framing attachment.

Fig. 3 is a view partly in plan and partly

in section taken on the line 3—3 of Fig. 2, on an enlarged scale;

Fig. 4 is a view in section taken on the line 4—4 of Fig. 3;

Fig. 5 is a view in section taken on the line 5—5 of Fig. 3; and

Fig. 6 is a fragmentary perspective view illustrating the guide for the short arm of the square and which arm is diagrammatically illustrated by means of broken lines.

The numerals 9 and 10 indicate the members of a straight edge bar spaced, one from the other, to form a longitudinal channel 11 and having one of their ends rigidly joined together by a transverse tie connection 12 with a work-engaging face located outward of the outer face of said straight edge bar. As shown, the members 9 and 10 of the straight edge bar are formed from angle bars, the corresponding flanges of which are indicated by the numerals 13 and 14. The flanges 13, which form the face of the straight edge bar, project in opposite directions and in the same plane, while the flanges 14 are turned back to back and project rearward from said straight edge bar.

To the other ends of the members 9 and 10 of the straight edge bar, are secured two quadrantial plates 15 and 16, respectively, located, the one directly above the other with their axes aligned, the one with the other. These members 15 and 16 are formed from sheet metal and are etched, and known in the trade as plates 1 and 2, respectively. The members 15 and 16 have their segmental edges and their straight edges, which extend at right angles to the straight edge bar, reinforced by round rods 17, that are grooved to receive the respective edges of said members. The straight edges of the members 15 and 16 which extend parallel to the face of the straight edge bar, are turned outward to afford work-engaging faces 18 and which faces also reinforce said members. It is important to note that the work-engaging faces 18 are located in the same plane with the work-engaging face of the connection 12 and hold the straight edge bar parallel to and spaced apart from the work 21, as indicated in Fig. 1.

A guide sleeve 19 is mounted between the quadrantial members 15 and 16 for swinging movement and in cross section is of rectangular form to receive and hold the long arm of a steel square 20, with shoulder 21

thereon, so as to hold the square 20 in a vertical position. The shoulder 21 is provided with a slot 22, through which the square 20 may be moved laterally, as indicated in Fig. 3.

for endwise sliding movement. Said guide 19 holds the long and short arms of the square 20 in the slot 11. This guide sleeve 19, at its inner corner and the one nearest 5 the work-engaging faces 18 of the members 15 and 16, is provided with a hub 21 having a pair of axially alined and oppositely projecting screw-threaded studs 22 mounted in bores 23 formed in the members 15 and 16, 10 at their axes. The flanges 13 of the straight edge bar terminate at the members 15 and 16 and, as one means for rigidly securing said members to the straight edge bar, the flanges 14 are extended between said members 15 and 20 rigidly secured thereto by rivets 24. The flanges 14, at the studs 22, are expanded, so that the bores 23 may be extended therethrough and thereby afford additional bearing surface for said studs. 25 Binding screws 25 have screw-threaded engagement with the edge portion of the guide sleeve 19, opposite from the hub 21, and impinge against the adjacent edge of the long arm of the square 20 to hold the same in said sleeve. It will be noted that the inner face of the edge of the guide 19, adjacent to the outer edge of the long arm of the square 20, extends radially from the axes of the members 15 and 16 and the 30 binding screw 25 securely and frictionally holds the same thereagainst, so that said outer longitudinal edge of the long arm of the square 20 is also on a true radial line, with respect to said members 15 and 16. Pivoted to the studs 22, for swinging movement over the outer faces of the members 15 and 16, is a pair of indicating bars 26 having reading edges, located in the same plane with the outer edge of the main 35 arm of the square 20, for coöperation with the graduations on said members. The outer ends of the indicating bars 26 are connected, the one with the other and to the guide sleeve 19, for common swinging movement therewith by a pair of oppositely projecting screw-threaded studs 27, rigidly secured to a hub 28 integrally formed with the outer end of the guide sleeve 19 on the same edge thereof with the hub 21. 40 Thumb-nuts 29, on the outer ends of the studs 22, hold the guide sleeve 19, members 15 and 16 and indicator bar 26 in assembled relation. The studs 27 are also provided with thumb-nuts 30, for frictionally clamp- 45 ing the edge portions 17 of the members 15 and 16 onto the guide sleeve 19 and thereby hold the same in different adjustments, with respect to each other. A U-shaped guide 31 for the short arm 50 of the square 20 has its transverse portion extended across the face of the straight edge bar and its prongs embrace the flanges 13 and are notched at 32 to receive the same, and thereby slidably hold the guide 31 on 55 the straight edge bar. A pair of fingers 33

on the guide 31 engage the opposite faces of the short arm of the square 20 and hold the same against lateral movement. The guide 31 is held in different adjustments on the straight edge bar by a pair of binding 70 screws 34, having screw-threaded engagement with the prongs of said guide and impinging against the flanges 14. It will be noted that the outer surface of the transverse portion of the guide 31 is in the same 75 plane with the work-engaging surface of the tie connection 12 and the work-engaging surfaces 18 of the plates 15 and 16 and also affords a work-engaging surface, which co-operates with the work-engaging surfaces 80 18, when the tie connection 12 projects beyond the work. Marked or otherwise indicated on the outer face of the straight edge bar, are two longitudinally extended scales 85 35, with their zero points located at the axes of the members 15 and 16.

From the above description, it is evident that by loosening the set screws 25, the long arm of the square 20 may be moved endwise in the guide 19, so that its zero end, with 90 respect to the scale on its outer longitudinal edge, may be set different distances from the axes of the members 15 and 16. By loosening the thumb-nuts 29, the guide 19 may be swung between the members 15 and 16 to 95 set the arms of the square 20 in different predetermined angular positions on the work X by the use of the indicating bars 26 and coöperating graduations on said members. Also by swinging the guide 19 on its 100 pivot, the zero end of the short arm of the square 20 may be set different distances from the working face of the straight edge bar.

Referring now to some of the different 105 uses of the improved framing attachment, for instance, if a hip rafter is to be cut for a four-sided or common roof having a one-third pitch or an eight inch rise per foot run, the mark indicated at 12 on the outer 110 longitudinal edge of the long arm of the square 20 will be set at the axes of the members 15 and 16, and the mark indicated at 8 on the outer longitudinal edge of the short arm of the square will be set at the working 115 face of the straight edge bar. With the square thus positioned, its long arm will give the level or seat cut and its short arm will give the plumb cut. The length of the rafter may be obtained by noting the reading of the scales 35 at the inner section of the outer longitudinal edge of the short arm of the square with the working face of the straight edge bar, towit: eighteen and three-fourths inches. Or, if taken in feet, will 120 give the length of a hip rafter for a twenty-four foot house.

To secure parallel or proportional cuts for timbers of different lengths, it is only necessary to adjust the long arm of the square 20 130

endwise in the guide 19. To vary the pitch of the roof from that just described, the thumb-nuts 30 are loosened to release the guide 19 and thereby permit the square 20 to 5 be set in different angular adjustments, with respect to the straight edge bar.

For the purpose of this case, it will not be necessary to fully illustrate the graduations and printed instructions on the segmental 10 members 15 and 16, as they are fully covered by copyrights issued to me. By following these printed instructions on the members 15 and 16, a mechanic may readily adjust a square with respect to the straight edge bar 15 to indicate any desired cut or cuts to be made in framing a roof or other structure. It is also possible for a mechanic to measure an angle by placing the long and short arms of his square into the angle to be measured, 20 and then taking the reading at a point where either of the indicator bars 26 intersect the graduations indicated on the segmental outer edge of the respective members 15 and 16. Also, by taking the reading of this same 25 angle, a mechanic may set his miter box saw to make a cut on the same angle.

It is, of course, understood that the square 20 may be placed on the attachment in reverse order from that shown in the drawings, and, in which case, the small arm of the square would be held in the guide 19.

What I claim is:—

1. The combination with a carpenter's square, of a straight edge bar having a pair 35 of laterally spaced graduated segmental plates, a guide for holding the square between said plates and in different adjustments with respect to the straight edge bar, and an indicator bar coöperating with the 40 graduations on each of the segmental plates, said guide and indicator bar being pivoted for swinging movement around the axis of said plate.

2. The combination with a carpenter's 45 square, of a straight edge bar having a pair of laterally spaced graduated segmental plates, a guide for holding the square between said plates and in different adjustments with respect to the straight edge bar, 50 and an indicator bar coöperating with the graduations on each of the segmental plates, said guide and indicator bar being pivoted and connected for common swinging movement around the axis of said plate.

55 3. The combination with a carpenter's square, of a straight edge bar having a graduated segmental plate, a sleeve-like guide pivoted for swinging movement around the axis of said plate and adapted to hold one 60 of the arms of the square with freedom for endwise sliding movement therein, one of the inner edge surfaces of said guide ex-

tending radially from the axis of said plate, and means for clamping one of the longitudinal edges of the arm of the square in the 65 guide against its radial inner edge surface.

4. The combination with a carpenter's square, of a straight edge bar having a longitudinal channel adapted to receive the square, a pair of segmental plates secured to 70 the straight edge bar on opposite sides of the channel therein, and a guide pivoted at the axis of said plates for swinging movement therebetween and adapted to receive and hold one of the arms of the square with freedom for endwise adjustment. 75

5. The combination with a carpenter's square, of a straight edge bar having a longitudinal channel adapted to receive the square, a pair of segmental plates secured to 80 the straight edge bar on opposite sides of the channel therein, a guide pivoted at the axis of said plates for swinging movement therebetween and adapted to receive and hold one of the arms of the square with freedom for 85 endwise adjustment, and means for securing said guide in different angular adjustments with respect to the plates.

6. The combination with a carpenter's square, of a straight edge bar having a longitudinal channel adapted to receive the square, a pair of graduated segmental plates secured to the straight edge bar on opposite 90 sides of the channel therein, a guide for holding one of the arms of the square with 95 freedom for endwise adjustment, and a pair of indicator bars coöperating with the graduations on the segmental plates, said guide and indicator bars being pivoted and connected for common swinging movement 100 around the axes of said plates.

7. The combination with a carpenter's square, of a straight edge bar having a longitudinal channel adapted to receive the square, a pair of graduated segmental plates 105 secured to the straight edge bar on opposite sides of the channel therein, a guide for holding one of the arms of the square with freedom for endwise adjustment, a pair of indicator bars coöperating with the graduations on the segmental plates, said guide and indicator bars being pivoted at the axes of 110 said plates, and means connecting the indicator bars to the guide for common swinging movement therewith and for securing the 115 same in different adjustments with respect to said plates.

In testimony whereof I affix my signature in presence of two witnesses.

JOHN D. WALL.
